INVENTOR

CLYDE C. FARMER

BY *John M. Cady*
ATTORNEY

UNITED STATES PATENT OFFICE.

CLYDE C. FARMER, OF EDGEWOOD, PENNSYLVANIA, ASSIGNOR TO THE WESTINGHOUSE AIR BRAKE COMPANY, OF WILMERDING, PENNSYLVANIA, A CORPORATION OF PENNSYLVANIA.

PLUG-IN SWITCH DEVICE.

Application filed March 25, 1921. Serial No. 455,602.

To all whom it may concern:

Be it known that I, CLYDE C. FARMER, a citizen of the United States, residing at Edgewood, in the county of Allegheny and State of Pennsylvania, have invented new and useful Improvements in Plug-In Switch Devices, of which the following is a specification.

This invention relates to plug-in switches, 10 and more particularly to a switch for use on cars of a train.

It has heretofore been proposed to provide an electric train signalling system in which the engineer or motorman may signal to an operator on the cars or the conductor or brakeman may signal the engineer.

With a system of the above character, it is desirable to reduce the amount of current used as much as possible and so the signal 20 circuit on each car is normally left open and must be closed by a plug-in switch before signalling can be carried on, and furthermore, it is desirable to prevent the use of the signalling system except by authorized persons.

The principal object of my invention is to provide a plug-in switch for the above purpose which can only be operated by a person having a prescribed key adapted for 30 closing the circuit through the plug-in switch.

In the accompanying drawing; Fig. 1 is a plan view of a plug-in switch embodying my invention; Fig. 2 a section of the switch 35 on the line 2-2 of Fig. 1, showing the position of the parts with the key removed; Fig. 3 a similar section, showing the operating key in position in the switch; and Fig. 4 an elevational view of the key.

As shown in the drawing, the plug-in switch may comprise a casing 1 having a chamber 2, containing a block 3 of insulating material. Fitted in the block 3 are two contact terminals 4 having connection to 40 the ends of a signal wire 5 and provided with radial contact lugs 6.

For closing the circuit in the plug-in switch through the wire 5, a key 7 may be provided, as shown in Fig. 4. Said key may have a round shank portion 8 with radially 50 projecting contact lugs 9 at the outer end.

The open end of the chamber 2 is closed by a cap 10 of insulating material in which is molded an escutcheon plate 11 having an

opening therethrough which corresponds in 55 contour with the contour of the contact lug end of the key 7.

The plate 11 is provided with an inwardly projecting sleeve portion 12 which acts as a stop for a movable member 13 subject to 60 the pressure of a coil spring 14.

The key slot through the escutcheon plate 11 is arranged at right angles to the contact lugs 6, as shown in the drawing.

In operation, when the key 7 is not in 65 position in the plug-in switch, the circuit through the wire 5 will be open and the member 13 is prevented from bridging the contact lugs 6 by engagement with the sleeve 12, as shown in Fig. 2.

If it is desired to close the circuit through the wire 5, a key 7 is inserted through the slot in the escutcheon plate 11, raising the member 13 against the resistance of spring 14. The key is then given a quarter turn, 75 so that the contact lugs 9 thereon will align with the contact lugs 6. When the hand is removed from the key, the spring 14 through the member 13 will press the key lugs 9 into firm engagement with the lugs 6, the sleeve 12 being slotted at the points 80 15 so as to permit the necessary movement of the lugs 9.

It will now be seen that with the above 85 described construction, the circuit cannot be closed through the wire 5 except by the insertion of a key having a contour corresponding with the contour of the slot in the escutcheon plate, so that only authorized persons, provided with the proper key, can 90 manipulate the switch.

Having now described my invention, what I claim as new and desire to secure by Letters Patent, is:—

1. The combination with a plug-in switch 95 comprising a casing containing a pair of oppositely disposed contact members and having a key opening, of a key having oppositely disposed contact lugs and adapted to be inserted in the key opening and partially rotated to permit the contact lugs to bridge the contact members, a spring, and a movable member subject to the pressure of said spring for pressing the lugs into engagement with the contact members.

2. The combination with a plug-in switch comprising a casing containing a pair of oppositely disposed contact members and

having a key opening, of a key having oppositely disposed contact lugs and adapted to be inserted in the key opening and partially rotated to permit the contact lugs to bridge the contact members, a spring, a movable member subject to the pressure of the spring for pressing the lugs into engage-

ment with the contact members, and means for limiting the movement of said member upon withdrawal of the key.

10

In testimony whereof I have hereunto set my hand.

CLYDE C. FARMER.
